UNITED STATES PATENT OFFICE.

CHARLES C. BLAKE, OF BROOKLINE, MASSACHUSETTS, ASSIGNOR TO C. C. BLAKE, INCORPORATED, OF BOSTON, MASSACHUSETTS, A CORPORATION OF NEW YORK.

PROCESS FOR MAKING SHOES.

Application filed April 28, 1921. Serial No. 465,131.

The present invention relates to the manufacture of shoes, and more particularly to the manufacture of welt shoes.

In my Patent No. 1,261,741, granted to me April 2, 1918, I have described a method of making welt shoes which consists in assembling an upper and insole on a last, stretching the upper into conformity with the contour of the last about the toe of the last, temporarily securing the upper in stretched position by applying a binder tightly around the toe exteriorly of the periphery of the shoe bottom, securing the upper directly to the insole by securing means extraneous of the binder, and thereafter removing the binder. The binder employed is a piece of flexible binding material which bears against the extreme toe end of the shoe and which is secured in position around the toe of the shoe by a pair of clamps arranged to engage the binder at points adjacent the ball line of the shoe on opposite sides thereof. I find that this flexible binder tends to bridge across the upper between the extreme toe end of the shoe and the securing clamps thus tending to release the upper slightly so that it does not have continuous contact with the edge face of the insole around the forepart.

The object of the present invention is to devise a method of making shoes by which the stretched upper may be temporarily secured in its stretched position in continuous and positive engagement with the edge face of the insole.

To the accomplishment of this object, and such others as may hereinafter appear, the various features of the invention relate to certain methods of making shoes hereinafter described and then set forth broadly and in detail in the appended claims which possess advantages readily apparent to those skilled in this art.

The various features of the present invention will be readily understood from an inspection of the accompanying drawings showing the best method of practising the invention at present known to the inventor, in which,

Figure 1 is a perspective of the shoe lasted in accordance with the present invention;

Fig. 2 is a sectional elevation of the shoe shown in Fig. 1;

Fig. 3 is an underside plan of the lasted shoe;

Fig. 4 is a plan of the formed binder;

Fig. 5 is a plan of the formed binder in position on the outside face of the guiding flange of a leader;

Fig. 6 is a side elevation of the lasted shoe after the binder has been removed mounted on a jack attached to the leader;

Fig. 7 is a rear sectional elevation of the parts shown in Fig. 6;

Fig. 8 is a rear sectional elevation showing the method of forming the binder on the leader;

Fig. 9 is a plan showing the preliminary step in the formation of the binder; and

Fig. 10 is a plan of the mechanism shown in Fig. 9 but in a different position in order to show how the binder is wrapped around the forepart of the leader.

Referring now to Figs. 1 to 4 an insole 1 and an upper 2 are first assembled on a last 3. The upper is then stretched to conform it with the contour of the last about the toe thereof. After the upper is stretched or updrawn a formed binder 4 is snapped into place to bind the stretched upper against the edge face 5 of the insole from a point adjacent the juncture of the ball and shank on one side of the shoe around the toe to a point adjacent the juncture of the ball and shank on the other side of the shoe. The binder 4 is held in place to prevent accidental displacement by a wire 6 passing across the shoe through holes formed in the upstanding skirt of the upper and secured to the offset ends 7 of the binder.

The binder 4, previously to its application to the stretched upper, has been shaped or formed, as will presently appear, to accurately fit about the forepart of the insole and hold the updrawn upper positively in contact with every point on the edge face of the insole around the forepart thereof.

After the binder has been applied to the shoe a fillet of cement is applied to the edge face of the insole, as described in my patent 100 hereinbefore referred to, in order to directly secure the upper to the insole by means extraneous of the binder. After the cement is dry the binder 4 is removed and the lasted shoe is then ready for the welting operation.

In order to prepare the lasted shoe for the welting operation it is mounted on a jack 8 of the saddle and spindle type secured to a leader 9. This leader is provided with a 110

guiding flange 10 having a beveled upper edge (Fig. 7) and the jack 8 is mounted on the leader so that the projections of points on the edge face 5 of the insole of the shoe 5 on the jack coincide with the inside face of the guiding flange 10 except at the toe of the leader where there is a slight variation to allow for the toe box. If the toe box is considered, for purposes of illustration, as a 10 part of the insole then the projections of the edge face of the insole coincide with the inside face of the guiding flange 10 entirely around the leader. The leader carrying the jacked shoe is inserted into an automatic 15 machine in which the leader is actuated to transfer the point of operation of the welt- ing tools around the shoe.

It will be thus apparent to those skilled in the art that the inside face of the guiding 20 flange 10 bears a definite relation to the edge face of the insole and I propose to take ad- vantage of this relation in the formation of the binder 4.

To this end I mount the leader 9 upside 25 down on a slide 11 (Figs. 9 and 10). In this position the beveled edge of the leader flange 10 faces the slide. The leader is clamped to the slide so that it is spaced somewhat above the surface thereof (Fig. 30 8). This is done so that where the binder is wrapped around the outside face and under the bevel of the guiding flange its inner surface will be spaced from the inside face of the guiding flange a distance equal to the 35 thickness of the upper 2 (Fig. 2). It will be understood that the angle of the bevel, diameter of the binder and spacing of the leader from the slide, are all so chosen as to gain the result just described.

40 The slide 11 is mounted to slide on ways 12 on the table 13 and is actuated along the ways by a handle 14 pivoted on the table 13 and connected to a block 15 on the slide through a link 16 pivoted to the block and 45 handle respectively.

When the slide 11 is in the position of Fig. 9 a hot wire is laid upon the table so that its middle portion is engaged with the toe portion of the leader. One end of the 50 wire is laid in a slot 17 formed near the end of an arm 18 pivoted on a bar 19 secured to the table 13. The other end of the wire is laid in a slot 20 formed in an arm 21 pivoted to the bar 19. The arms 18 and 21 tend to 55 approach under the influence of a coiled spring 22 one end of which is connected to the arm 21 and the other end of which is connected to an extension 23 on the arm 18.

The arms 18 and 21 are held apart against 60 the influence of the spring 22 by the sloping sides 24 on the slide 11 which engage pins 25 depending from the arms. When the slide 11 is actuated from the position of Fig. 9 to that of Fig. 10 the pins 25 slide 65 along the sloping sides 24 to allow the arms

18 and 21 to gradually approach and thus wrap the hot wire around the forepart of the leader.

In order to position the ends of the hot wire against the leader at the reverse curves 70 at the juncture of the ball and shank of the leader, the arms 18 and 21 carry a bar 26 which slides loosely through the arms near the ends thereof. The bar 26 is normally held in position by a coiled spring 27 one 75 end of which is connected to the bar and the other end of which is connected to an extension 28 on the arm 21.

When the slide 11 is moved into the position of Fig. 10 a pawl 29 is engaged with 80 teeth 30 formed on the bar 26, the pawl being held in position by a spring 31 carried by the arm 18. The arms 18 and 21 are then moved towards one another to position the binder along the reverse curves at the 85 juncture of the shank and ball through continued manipulation of a handle 32 which is pivoted on the slide 11 and which engages the side of the bar 21.

In order to form the lateral extensions 7 90 (Figs. 3 and 4) on the wire the slots 17 and 20 on the arms 18 and 21 are formed to properly receive the wire in the position of Fig. 9 and bend the wire in the final position of Fig. 10.

In making shoes by my improved method the binder is formed on the leader and then the leader, or one identical with it, is mounted on a jack carrying a last and an un- 100 trimmed insole. The leader and jack are then placed in an automatic rounding ma- chine in which the insole is trimmed to such size that the projections of points on the edge face of the insole upon the plane of the leader coincide with the inside face of the 105 guiding flange on the leader, except at the toe of the insole where there is a slight va- 110 riation to allow for the application of the toe box. The last with the trimmed insole is then removed from the leader and an up- 115 per containing the toe box is assembled on the last and updrawn to stretch it in con- formity with the upper shaping surface of the last. The formed binder is then snapped into place to bind the stretched upper to the 120 edge face of the insole.

After the binder is secured in place a fillet of cement is inserted between the upper and the edge face of the insole to secure the upper thereto. The binder is then removed the lasted shoe is again jacked upon the leader and the leader and jack are then placed in an automatic machine which se- 125 cures the welt, upper and insole together either by thread or metallic fastenings. Upon its removal the welted shoe is finished in the usual manner.

What is claimed as new is:

1. That improvement in the art of making 130 shoes which consists in forming a leader,

trimming an insole to an outline determined by the leader, applying a piece of material on the leader to form a binder having a definite relation to the edge of the trimmed insole, assembling an upper and the insole on a last, stretching the upper into conformity with the contour of the last about the toe of the last, temporarily securing said upper in stretched position by applying the formed binder, securing the upper directly to the insole by securing means extraneous of the binder, and removing the binder.

2. That improvement in the art of making shoes which consists in producing a formed binder to bear a definite relation to the edge face of an insole, assembling an upper and the insole on a last, stretching the upper into conformity with the contour of the last about the toe of the last, temporarily securing said upper in stretched position to the edge face of the insole by applying the formed binder, securing the upper directly to the edge face of the insole by securing means extraneous of the binder, and removing the binder.

3. That improvement in the art of making shoes which consists in forming a leader having a guiding flange, trimming an insole to cause its edge to bear a definite relation to

the guiding flange, producing a formed binder to bear a definite relation to the guiding flange, assembling an upper and the insole on a last, stretching the upper into conformity with the contour of the last about the toe of the last, temporarily securing said upper in stretched position by applying the formed binder, securing the upper directly to the insole by securing means extraneous of the binder, and removing the binder.

4. That improvement in the art of making shoes which consists in forming a leader having a guiding flange, trimming an insole to bear a definite relation to the inside face of the guiding flange, forming a binder on the outside face of the guiding flange as a templet, assembling an upper and the insole on a last, stretching the upper into conformity with the contour of the last about the toe of the last, temporarily securing said upper in stretched position by applying the formed binder, securing the upper directly to the insole by securing means extraneous of the binder, and removing the binder.

In testimony whereof I have signed my name to this specification.

CHARLES C. BLAKE.
